PUMP

George Nisula, Edgewater, Wis.

Application January 13, 1938, Serial No. 184,829

2 Claims. (Cl. 103—183)

My invention relates to improvements in pumps such as used for raising water from deep wells, either by hand power or other available power such as the reciprocating rod of a wind-mill.

The main objects of the invention are to produce a steady flow of water and to simplify the general structure particularly as to the subsurface parts. Other objects and advantages of the device will hereinafter be fully described reference being had to the accompanying drawing, in which:

Fig. 1 is a top view of the pump with hand lever operating means.

Fig. 2 is a partly sectional rear elevation of my improved pump as seen from the side opposite the water spout, and a wind-mill rod shown additionally and connected to the hand lever.

Fig. 3 is a right side elevation of Fig. 2 omitting the hand lever, and Fig. 4 is a sectional elevation in horizontal plane as on line 4—4 in Fig. 2.

Referring to the drawing by reference numerals, similar characters designating corresponding parts in the various views; 5 represents any platform on which the base flange 6F of the main pump housing 6 is secured at 7.

Said housing comprises a water chamber 6C at a predetermined height over the base and 8 designates a water outlet spout directed outwardly from the chamber, that part of said chamber above the outlet comprising an air chamber.

From the bottom of the said chamber 6C extends downwardly a pair of parallel pipes 9R—9L running into the ground in close parallel relation, the lower extremities of said pipes connected as at 10 to a dual bore piston block 11, the lower parts of the bores thereof connected with a Y-pipe 12 the single lower extremity of which comprises a water intake duct 13. The bores of block 11 each have a piston 14 and a piston rod of which the right hand one is designated 15R and the left hand one 15L extending upwardly within pipes 9R and 9L respectively, to and through the chamber 6C and above said chamber the rods are connected with reciprocating means which will now be fully described.

6A is an upright column extending vertically from the top of the chamber 6C, centrally, and bifurcated upwardly, each of the two parts comprising at its top a horizontal bar 6B forming a T-shaped head, said bars parallel and registering horizontally.

At the outer extremities of said bars 6B they are bored to retain the shaft 16 of a roller 17. Centrally of said bars 6B they are bored to ro-

tatably retain a shaft 18 of a gear 19 rotatable of course in a vertical plane and between the arms or bars 6B and in a common plane with the rollers 17.

Between each roller 17 and the gear is placed 5 a vertically reciprocable toothed rack 20 the teeth of which continuously mesh with the teeth of the gear 19 and are held thus in mesh each by its roller 17. Each rack 20 is bored longitudinally to retain the vertical shank of an L-shaped 10 member 21 the lower horizontal arm of which is bored to receive and retain the upper end part of a rod 15R—15L.

Gear 19 is keyed to shaft 18 and the said shaft protrudes from both sides of the bars 6B, 15 said protruding parts having suitable key means represented by a removable key 22 for retaining the fulcrum part of a pump handle 23, at either or both sides.

It will now be readily understood that when 20 the pump handle 23 is oscillated in the usual manner, in vertical plane, and as designated by the arrows 24, the gear 19 will move the rods 15R—15L simultaneously, one up and the other down, and vice versa in reciprocating action and 25 operating the pistons 14 to raise water to the chamber 6C and outlet of water from the spout will be practically and to all intents and purposes a continuous stream.

Assuming that water is raised into the chamber 30 in considerable volume and to a level at or over the outlet 8, that part of the chamber above the outlet automatically becomes a compression air 35 chamber in which the natural reaction of the compression therein over the water level tends to equalize the discharge of water particularly at the instant that the strokes of the piston rods are changing direction.

It is understood of course that the pistons 14 and the ducts of pipe 12 are provided with necessary valves 25 and 26, respectively, to direct and 40 check upward movement of the water in accordance with the piston movement. For example, in Fig. 1 the left hand piston rod 15L may be assumed to be moving downward, the corresponding check valve 26 is closed and water thereabove circulates through the valves 25 over the piston and is subsequently forced upward by the piston on its upward stroke.

Each upward stroke of the piston draws water 45 into the chamber below it.

The toothed racks 20 as above described are of course tubular, and the bars 21 may be retained 50 adjustably in their bores by means of set screws 55

27 or equivalent means. The toothed rack may of course be an integral part of bar 21.

In Figs. 2 and 3, 28 designates the lower extremity of a reciprocating pump rod of a windmill which may be connected by means of a link 29, at 30 to the lever 23, or any other mechanical connection of the rod may be made to cause reciprocating action of the pump rods 15R and 15L.

10 I am aware that a number of mechanical devices have been made for the purpose described. However my construction embodying the compactly constructed sub-surface parts as described and illustrated are highly efficient and practical. 15 It will be readily understood too that a housing may be made to inclose the reciprocating and other moving parts (except the handle 23) and other modifications may be embodied without departing from the scope and spirit of the invention.

20 I claim:

1. A pump of the class described comprising an upright frame with a hollow base adapted to be secured to a platform, an integral upwardly directed arm from the top of said base portion and bifurcated upwardly the upper termini of said bifurcated arm comprising a pair of horizontally registering arms forming a T-shape with

said bifurcated part, a water chamber in the upper part of the hollow base and an outlet spout directed outwardly therefrom, dual pipe conductors extending downwardly from said water chamber and parallel to each other, the lower extremities of said conductors comprising a pair of cylinders, a piston in each cylinder and a piston rod extending upwardly within each conductor and over the hollow housing, means mounted over said housing in said bifurcated part for simultaneously reciprocating the pistons one up and one down, alternately, a Y-pipe connected to the lower ends of the cylinders and valve means in said Y-pipe to permit upward passage of water to the cylinders alternately and 10 to shut off downward passage of water.

2. The structure specified in claim 1, in which 15 said piston reciprocating means comprises a gear rotatably mounted on a shaft centrally of and in the bifurcated part of the housing, a pump handle keyed on said gear shaft, a pair of upright rack bars meshing with the teeth of said gear at diametrically opposite sides thereof, each rack bar directly connected to a piston rod, means in the T-head guiding said rack bars and holding 20 them in mesh with said gear.

GEORGE NISULA.
